(57) **CLAIM**

The ornamental design for an illuminating handle for a toy, as shown and described.

DESCRIPTION

FIG. 1 is a perspective view of an illuminating handle for a toy, showing our new design;

FIG. 2 is a front elevational view thereof;

FIG. 3 is a rear elevational view thereof;

FIG. 4 is a top plan view thereof;

FIG. 5 is a bottom plan view thereof.

FIG. 6 is a right-side elevational view thereof; and,

FIG. 7 is a left-side elevational view thereof.

The broken lines showing illuminated transparent prismatic balls in FIGS. 1 and 4-7 are included for the purpose of illustrating the invention in use, and form no part of the claimed design.
